A. Bluhm,
Attorney.

UNITED STATES PATENT OFFICE.

HOMER F. LIVERMORE, OF BOSTON, MASSACHUSETTS.

DROP-WIRE BAR FOR LOOMS.

Application filed January 24, 1922. Serial No. 531,495.

To all whom it may concern:

Be it known that I, HOMER F. LIVERMORE, a citizen of the United States, residing at Boston, in the county of Suffolk and State of 5 Massachusetts, have invented certain new and useful Improvements in Drop-Wire Bars for Looms, of which the following is a specification.

In certain well known kinds of looms, it 10 is customary to provide a warp-stop whereby the breaking of any of the warp threads will cause the machine to stop at once. In accomplishing this, a thin steel bar slidably carries a series of slotted members or "wires" 15 each supported by a warp thread and so disposed that when a thread breaks, the associated wire drops a short distance and by its entrance between certain approaching jaws holds the latter from closing and thereby 20 stops the loom.

The difficulty with this arrangement is that the slotted ends of such thin steel bar frequently break away and thereby render the entire bar useless, and a new one must be 25 provided, entailing not only the loss of the old bar, but necessitating considerable loss of time in threading all the drop wires upon the new bar.

The object of this invention is the construction of means whereby all such broken bars can be used again, as well as rendering 30 it easier and more economical in fitting new bars to their task.

In the drawings forming part of this specification, Fig. 1 is a perspective view of a part of such a drop-wire bar and associated members showing my means for attaching its end to the well-known supporting casting. Fig. 2 is a side view of the terminal portions of 35 the bar showing my attaching devices connected therewith, one of the devices being in section. Fig. 3 is a top view of the same, with one of the attaching devices in section.

Referring to Fig. 1, the reference numeral 40 45 1 designates a drop-wire bar, 2 are two of the drop-wires, 3 is one of the rocking jaws between which a dropped wire descends and stops the loom, and 4 is one of the supporting castings having a lug 5 to which an end of 50 the bar 1 is customarily fastened.

Each of the large number of drop-wires 2 has an elongated slot 6 loosely penetrated by

the bar 1 and supported as by a thread or wire 7 from a warp thread passing freely through it, in a well known manner.

The attaching device for each end of the bar 1 consists of a casting or forging 10 having a socket 11 disposed to receive an end of the bar 1, the latter being fastened therein by set screws 12, as shown in Figs. 2 and 3; and a slotted ear 13, the slot 14 therein being made sufficiently long to fit the distance between the lugs 5 should the bars 1 not be cut to exact length. Through this slot 14 is inserted a bolt 15 through the lug 5 in the usual manner.

In order to accommodate the new attaching device to looms now on the market, the under wall 16 of the socket 11 is made very thin, and its top wall 17 made extra thick to 70 provide the necessary strength, and in addition to such thickness of wall, the sides and top are provided with a rib 19, each side 20 having a boss 21 for the passage of the set screws 12. As illustrated in Fig. 3, each 75 ear 13 is made of substantially the same thickness as the bar 1 in order that the same bolts 15 may be used as those formerly employed.

In order to utilize an old bar 1, whether 80 terminally broken or otherwise, its ends are cut square off to the proper length and inserted in the socket 11. Then, the screws 12 being set tightly up, and the bolts 15 introduced through the slots 14 and lugs 5 and 85 suitably turned up, the bar is ready for use.

The drop-wires 2 are, of course, strung upon the bar before one or both the attaching devices have been thus applied to the bar.

What I claim is:

1. A drop-wire bar for looms, comprising a length of thin bar, and an attaching member for the end thereof, said member consisting of a socket for receiving the bar-end, 95 fastening means for retaining it therein, and a slotted ear.

2. A drop-wire bar for looms, comprising a length of thin bar, and an attaching member for each end thereof, the said member 100 consisting of a socket and a thin slotted ear, the socket walls being strengthened above the bar, and the ear being substantially equal in thickness to said bar,

3. A drop-wire bar for looms, comprising a length of thin bar, and an attaching device for each end thereof, said device consisting of a socket for receiving an end of the bar, the socket having its top wall considerably thicker than its bottom wall, a boss on each side, a rib on the sides and top, and

a thin slotted ear at its end, and set screws in said bosses for locking the bar-end in place.

In testimony that I claim the foregoing invention, I have hereunto set my hand this 16th day of January, 1922.

HOMER F. LIVERMORE.
